US0D1037715S

(12) **United States Design Patent** (10) Patent No.: **US D1,037,715 S**
(45) Date of Patent: ** Aug. 6, 2024

(54) **AIR-BED**

(71) Applicant: **Yongbin Zhao**, Zhoukou (CN)

(72) Inventor: **Yongbin Zhao**, Zhoukou (CN)

(**) Term: **15 Years**

(21) Appl. No.: **29/922,527**

(22) Filed: **Dec. 22, 2023**

(51) LOC (14) Cl. **06-09**

(52) U.S. Cl.

USPC **D6/604**

(58) **Field of Classification Search**
